UNITED STATES PATENT OFFICE.

HARRY C. LEE, OF BROOKLYN, NEW YORK.

WIRE MASK.

SPECIFICATION forming part of Letters Patent No. 287,137, dated October 23, 1883.

Application filed August 20, 1883. (No model.)

To all whom it may concern:

Be it known that I, HARRY C. LEE, of Brooklyn, in the county of Kings and State of New York, have invented an Improvement in Wire Masks, of which the following is a specification.

Wire masks have been made for the use of base-ball players, to guard the face from concussion by the ball. These masks are rigid, and occupy considerable space. In my improvement the mask is made to fold, so as to occupy but little space in transportation. The mask can easily be adapted to faces of different shapes, and the wire is bent in such a manner as not to interfere with the movements of the head, and there is nothing to obstruct the vision as the eyes are turned in following a ball.

In the drawings, Figure 1 is an elevation of the wire portion of the mask. Fig. 2 is a plan showing the forehead-rest and the attaching device, and Fig. 3 is a side elevation of the mask.

The face-mask is made with the horizontal or nearly horizontal wires *a b c d* and the eye-bow wires *f* and *g*. The nearly-vertical wires *h i k l m* cross the other wires, and are fastened securely to them. Usually at the points of intersection the wires are partially notched or crimped, so as to set closely together, and the ends of the wires are bent around, as eyes, to receive the adjacent wire. At the junctions of the wires *h i k* and *h' i' k'* with the eye-bows *f* and *g* the ends of such wires *h i k h' i' k'* will usually be flattened quite thin, so as to be wrapped partially around such wires *f g* without any projections, so that a ball striking upon the eye-bows will be deflected laterally, and will not be detained or injured by projections. The ends of the wires *a b f g c* are bent us as eyes at the vertical central part of the mask, at which place there is a wire, *n*, that forms a hinge-pin, it being understood that the mask is made with two half-sections united together at the center of the mask. By this construction the two halves of the mask can be pressed together and occupy but little space, or they can be opened more or less to suit the wants of the person wearing the same. The spring of the wires will allow the halves of the mask to be swung on this hinge-pin *n*, notwithstanding the fact that this pin will usually

be an arc of a circle, to conform to the general shape of the mask. This pin can be drawn out if it is desired to separate the halves of the mask for convenience for transportation.

55

The halves of the mask are to be made sufficiently large to allow them to occupy an inclined position to each other and reach across to the sides of the face, so that a ball will be deflected by the inclination, and the nearer 60 the back edges of the halves of the mask are brought together the more the center will project. This allows for the preferences of the wearer being accommodated, and for the mask to be adjusted to wide or narrow faces. In 65 order to hold the mask when so adjusted, I employ the adjustable braces *p* and *q*, one at the upper and the other at the lower part of the mask. The bars that compose these braces are looped at their fixed ends around the 70 wires *k* and *m'*, respectively. The free ends lap, and one is provided with a stud, the other with holes, so as to vary the length of the braces, and there are sliding clips *r r'* upon the respective braces, to hold them together 75 after adjustment. The braces maintain the back edges of the mask at the proper distances apart.

Upon the wires *l m l' m'* there are cushions *t t'*, that rest against the sides of the face and 80 form yielding bearings for the mask.

Across between the wires *kk* there is a leather strap, *u*, that is sufficiently wide to take a bearing upon the chin and form a chin-rest, and there is a similar strap, forming a forehead- 85 rest at *v*. These chin and forehead rests and the face-cushions, however, have been used in other wire masks.

There is a strap, *w*, extending from the forehead-rest in the form of a loop, through which 90 the top brace, *p*, passes. This preserves the forehead-strap in its proper position vertically.

The attaching-strap *y* passes around the back of the head from one wire *l* to the opposite wire, and it is usually of elastic webbing, 95 with a strap and buckle, as shown.

In masks that have heretofore been made the wire *k* passes across the eye-opening. This, however, sometimes interferes with the vision of the wearer. I extend the eye-bows *f g* around 100 to the wires *m m'*, and hence am able to leave the eye-bows open to the edge-wire *l*. At the

bottom of the mask the wires *l k* are united, or made as one, just below the bottom brace. This strengthens the parts, and to prevent contact of the mask with the chest, shoulders, or clothing of the wearer the wire *l* is inclined forward and outwardly to the lower end of the wire *k*, and in this wire *k* there are two bends, at 5 and 6, one above and the other below the wire *a*, to form stops, so that the chin-rest can be buckled to such wire *k* either above or below such wire *a*, and will be held in such position vertically by the stops 5 or 6 and wire *a*.

I claim as my invention—

1. The wire mask made of two halves united by a hinge in the center, and provided with the cushions and attaching-straps, substantially as set forth.

2. The combination, in a wire mask, of two halves with eyes at the ends of the wires at the middle of the mask, a wire passing through such eyes, and adjustable braces at the upper and lower parts of such mask, substantially as set forth.

3. The wire mask formed in two halves hinged together in the middle, with the eye-

bows *f* and *g* extending to the side wires, *m m'*, respectively, and united with the wire *l* at the edge of the mask, substantially as set forth.

4. In combination with the extension-brace *g*, the wires *k l* of the mask, extending down and united or formed in one, the wire *l* being inclined outwardly and forwardly to the wire *k*, for the purposes set forth.

5. In a wire mask, the combination, with the chin-rest, of the wire *k*, having bends or projections above and below the wire *a*, for retaining the chin-rest in either position in which it may be placed, substantially as set forth.

6. In combination with the two halves of the wire mask, hinged together, the adjustable brace *p* at the upper part of the mask, and the forehead-rest and a loop from such forehead-rest to the adjustable brace, substantially as set forth.

Signed by me this 14th day of August, A. 45
D. 1883.

H. C. LEE.
